(57) **CLAIM**

(21) Appl. No.: **29/343,944**

The ornamental design for a “finger loop for a beverage bottle,” as shown and described.

(22) Filed: **Sep. 22, 2009**

DESCRIPTION

(51) **LOC (9) Cl.** **09-07**

FIG. 1 is a top, front, and right side perspective view showing my new design for a finger loop for a beverage bottle;

(52) **U.S. Cl.** **D9/434; D7/622**

FIG. 2 is a front view of the finger loop for a beverage bottle shown in FIG. 1;

(58) **Field of Classification Search** D7/601,

FIG. 3 is a left side view of the finger loop for a beverage bottle shown in FIG. 1, the right side view being a mirror image thereof;

D7/602, 701, 705–706, 708, 619.1, 622;
D9/434, 455, 499; D34/28; 294/1.1, 27.1,
294/29; D3/202, 327; 206/142–143, 427;

FIG. 4 is a top view of the finger loop for a beverage bottle shown in FIG. 1;

220/694, 752–755, 758

FIG. 5 is a bottom view of the finger loop for a beverage bottle shown in FIG. 1;

See application file for complete search history.

FIG. 6 is a rear view of the finger loop for a beverage bottle shown in FIG. 1; and,

FIG. 7 is a top, front, and left side perspective view of the finger loop for a beverage bottle shown in FIG. 1 in a normal use environment on a beverage bottle.
